(57) **CLAIM**

The ornamental design for a square baluster connector, as shown and described.

DESCRIPTION

FIG. 1 is a top perspective view of the square baluster connector of the present invention.

FIG. 2 is a bottom perspective view of the square baluster connector depicted in FIG. 1.

FIG. 3 is a top plan view of the square baluster connector depicted in FIG. 1.

FIG. 4 is a bottom plan view of the square baluster connector depicted in FIG. 1; and,

FIG. 5 is a front side plan view of the square baluster connector depicted in FIG. 1, where rear and side plan views of the square baluster connector are identical to the front side plan view.
